JOHN HOUP, OF SPRINGFIELD, PENNSYLVANIA.

Letters Patent No. 88,960, dated April 13, 1869.

IMPROVEMENT IN SURFACE-CONDENSERS.

The Schedule referred to in these Letters Patent and making part of the same.

To all whom it may concern:

Be it known that I, JOHN HOUP, of Springfield, Bucks county, Pennsylvania, have invented an Improvement in Surface-Condensers; and I do hereby declare the following to be a full, clear, and exact description of the same.

My invention consists of a surface-condenser, constructed and arranged as fully described hereafter, in which, by the employment of a number of vertical tubes, closed at their upper ends, and of a certain arrangement of chambers, I am enabled to overcome the objections arising from the contraction and expansion of the tubes in ordinary condensers, and to effect a more thorough and rapid condensation of steam.

In order to enable others skilled in the art to make and use my invention, I will now proceed to describe its construction and operation, reference being had to the accompanying drawing, which forms a part of this specification, and in which—

Figure 1 is a longitudinal vertical section of my improved surface-condenser, and

Figure 2, a sectional plan view of the same, on the line 1-2, fig. 1.

The apparatus consists of a case A, made in the present instance of cast-iron, the interior of which is separated into four compartments, B, B¹, B², and B³, by the horizontal, inclined, and vertical partitions, c, d, and e, the upper compartment, or water-space B, containing a cluster of vertical tubes, F.

The lower ends of the latter are secured in the usual manner to the partition-plate c, and are open and communicate with the steam-space B¹, but the upper ends of the said tubes are closed, and are free to contract or expand without loosening or causing the joints at their lower ends to leak.

The cold water, which is caused to circulate among the tubes F, is first admitted to the apparatus through a pipe, h, into one end of the compartment B², passing entirely through the latter and through a pipe, i, before it enters the upper water-space B.

In the latter there is a partition, j, which causes the cold water to first flow towards the opposite end of the compartment, and to consequently circulate among the lower ends of all the tubes, and then to flow in a contrary direction above the partition and around the upper ends of the tubes, until it finally reaches the pipe k, through which it passes from the apparatus. (See arrows in fig. 1.)

H is the pipe through which the exhaust steam is admitted to the compartment B¹, and i are inclined tubes, forming a communication between the compartments B¹ and B², and intended for carrying off the water formed by condensation of the steam.

A pipe, m, communicating with the bottom of the compartment B³, leads to the air-pump.

The operation of my improved condenser is as follows:

Cold water is forced through the compartments B² and B as above described, and the necessary vacuum is maintained within the tubes F, and the steam-spaces with which they communicate, by means of the air-pump, as usual.

The exhaust steam is admitted to the compartment

B¹ through the pipe H, and immediately fills the vertical tubes F, which, as before described, are entirely surrounded by the water passing through the chamber B.

The steam is rapidly condensed by contact with the cold surfaces of these vertical tubes, and the water formed drops from the same on to the inclined partition d.

Flowing to the rear end of the partition, by reason of its inclination, the water enters the inclined tubes i, and in passing through the same towards the compartment B³, is cooled by the water contained in the chamber B².

It will be understood that the air-pump, with which the pipe m is connected, draws off this condensed steam, and acts in the usual manner in preserving a vacuum within the apparatus.

The advantages possessed by the above condenser over ordinary surface-condensers may be enumerated as follows:

First, in ordinary condensers, the tubes, which are generally placed in a horizontal position, are open at each end, and are so secured to rigid plates that they are not permitted to expand or contract, the joints consequently becoming loosened and leaky, and the operation of the apparatus imperfect.

In my condenser full provision is made for the contraction and expansion of the tubes, by securing them at their lower ends only, and permitting to their upper closed ends the slight motion due to these causes.

A second advantage arising from the employment of vertical tubes closed at their upper ends is, that a more thorough circulation of cold water can be maintained about them than with horizontal tubes, and that the condensation and cooling of the water formed are more thorough and rapid, inasmuch as the steam, which rises to the top of each tube, has to return through the same tube before it can again reach the chamber B¹.

The vertical tubes also possess an advantage over those placed in any other position, when the condenser is used in connection with marine engines, as the water of condensation is less likely to be directed into improper channels by the motions of the vessel; and to still further aid the air-pump, by directing the water towards it, the partition d and tubes i are somewhat inclined, as before described.

I claim as my invention, and desire to secure by Letters Patent—

1. The arrangement, in a surface-condenser, of vertical tubes F, open at their lower ends but closed at the top, substantially as herein described.

2. The vertical tubes F, closed at the top, in combination with chambers B, B¹, B², and B³, arranged in respect to each other and to the tubes, and communicating as set forth.

In testimony whereof, I have signed my name to this specification, in the presence of two subscribing witnesses.

JOHN HOUP.
